UNITED STATES PATENT OFFICE.

GEORGE L. HARVEY, OF CHICAGO, ILLINOIS.

TANDEM DRAFT-RIGGING.

1,004,797.

Specification of Letters Patent.

Patented Feb. 18, 1912.

Application filed April 17, 1910. Serial No. 229,662.

To all whom it may concern:

Be it known that I, George L. Harvey, a citizen of the United States, and resident of Chicago, in the county of Cook and State of Illinois, have invented certain new and useful Improvements in a Tandem Draft-Rigging, of which the following is a specification:

One of the necessities in connection with a draft rigging for railway cars of the present weight and capacity is that of providing adequate resistance by the use of means adapted to be contained within the limited space allowed. It has not been practical in straight spring resistance devices to utilize springs having the requisite capacity particularly if the rigging is designed to employ tandem springs having cumulative travel. I have so arranged the parts composing my rigging that high capacity springs may be utilized and cumulative travel secured, the total travel being kept within the permissible limits.

The desired result is secured by utilizing a vertical yoke having a key connection to the draw bar, the yoke being provided with an integral pocket in its rear end, the sides of the pocket at its rear extremity directly contacting the sill stops. One spring is mounted in the casing and another spring in front thereof which is contacted by a front follower engaging the front sill stops. A plate separates the two springs and abuts the forward extremities of the pocket. The draw motion is transmitted from the front follower to the rear spring by an axial plunger. It will be seen that by casting the spring pocket as a part of the yoke the rear spring is suitably confined without the necessity for a separate part held or fastened in the yoke and a full sized spring may be accommodated therein. Furthermore, that there is no limitation as to the size or capacity of the front spring element. The yoke and draw bar are joined by a key and slot connection, the key passing through but not normally contacting the ends of the slots formed in the sills. The key which connects the yoke and a standard draw bar is normally located at one end of the slot in the yoke, the length of the slot being equal to or greater than the total travel of the gear. Therefore it will be seen that the yoke is immovable on the bussing stroke and is

moved forwardly against the resistance of both springs on the draft stroke, with the front follower only as a stop.

The invention will be more readily understood by reference to the accompanying drawings, wherein,

Figure 1 is a longitudinal sectional view taken on a horizontal line through the axis of a rigging constructed in accordance with my invention;

Fig. 2 is a longitudinal vertical slot view;

Figs. 3 and 4 are sectional views on the lines 3-3 and 4-4 of Fig. 1;

Fig. 5 is an elevation showing the spring separating plate, and,

Fig. 6 is an elevation of the plunger employed.

In the drawings it will be seen that the metal sills 10, of the car are provided with forward stops 11, and rear stops 12. The butt end 13, of the draw bar is accommodated between the sills, the same being secured to the slotted side members 14, of the yoke by means of a key 15, the key engaging a slot in the draw bar. The key passes through suitable elongated apertures 16, in the sills. The yoke is of the so-called vertical type, the upper and lower arms 17, 18, being joined at their forward ends by the side members 14. The arms 17, 18, of the yoke extend rearwardly and are joined in the usual manner. At the rear end the yoke is provided with reinforced side walls 19, forming a cylindrical pocket adapted to accommodate a very large sized spring member 20. The sides of the yoke are so proportioned (as best shown in Fig. 4) as to fit between the sills, the rear side portions 21, abutting the stops 12, and serving to transmit bussing shocks to such stops. The casting may be made of massive proportions and still accommodate a very large spring element. The rear end of the yoke must be made of ample proportions as all the bussing shock is transmitted therethrough to the sills.

A second spring member 22, is located in front of the spring member 20, the forward spring being engaged by a front follower 23, at one end and at the other end by a bearing plate 24, which rests on the forward extremity of the pocket, as best shown in Fig. 1. A hollow plunger 25, is fitted at its front end

- over a projection 26, held on the front follower, its rear end 27, being enlarged to substantially the size of the spring 20, and being adapted to transmit motion thereto.
- 5 The flared end 27, fits within a similarly shaped aperture in the plate 24. In order to prevent the turning of the plunger I flatten one side thereof, as best shown at 28, (in Fig. 3) and the aperture 29, in the plate 24, is 10 similarly shaped. The reason for preventing the plunger from turning is that the forward end 30, thereof (as best shown in Figs. 1 and 6) is rounded slightly in a horizontal direction to accommodate the necessary canting of the front follower following the oscillation of the draw bar. The result might be secured by rounding the end of the plunger as in a sphere, but the area of contact would be less than when rounded as here shown; 15 therefore it is desirable to prevent the plunger from moving to a position where the curvature would be ineffective. It will be noted that a space separates the enlarged end 27, of the plunger and the rear spring 20. This is done in order that the springs may successively come into action both on pull and buff. I am aware that this in itself is not new, but in a construction such as herein disclosed it is novel and useful.
- 20 The end or head 27, of the plunger, which is seated in the countersunk opening in the plate 24, terminates in the plane of the forward end of the pocket formed by the walls 19. Thus the plate, the plunger, spring 22, and the front follower 23, may be inserted 25 in and removed from the yoke as a unit through the lateral opening therein. This enables the parts to be readily removed. By reason of the shape of the head 27, its extremity may be substantially the diameter of the spring contained within the pocket and its shank may be of such diameter as to be received within the center of the forward spring 22.
- 30 It will be noted that the separating plate 24, does not at any time engage stops on the sills, and that this plate, together with the yoke and pocket are immovable on the buffing stroke. On the draft stroke the forward 35 spring is first compressed and the rear spring then begins its duty. The yoke and associated parts move forward with the draw bar. The rigging is supported at its rear end by a transverse plate 31, in the usual manner.
- 40 The great and fundamental advantage in the use of a rigging such as described is that all the parts are adapted to be accommodated within the short space usually occupied by springs of small diameter and that notwithstanding this a tandem rigging is provided the same having cumulative travel with very large capacity springs. In order 45 to insert the gear between the sills the parts are assembled as shown and forced between the stops. The necessary initial compression is secured by driving the key 15, into position.
- I claim:
1. In a draft rigging, the combination of 70 a yoke having an integral barrel in the rear end thereof, a pair of full size cushion elements, one of which is accommodated in said barrel, a plate extending across the open end of the barrel and serving as a bearing for 75 the rear end of the forward cushion element, a front follower, a plunger extending from the follower through said plate and having a head adapted to bear on the forward end of the rear cushion element, and a draw bar 80 slidably engaging said yoke, substantially as described.
2. In a draft rigging, the combination of 85 a yoke having an integral barrel in the rear end thereof, a pair of full size cushion elements, one of which is accommodated in said barrel, a plate extending across the open end of the barrel and serving as a bearing for the rear end of the forward cushion element, a front follower, a plunger extending from 90 the follower through said plate and having a head adapted to bear on the forward end of the rear cushion element, said plunger terminating in the plane of the forward edge of the barrel, whereby the plunger, 95 plate and forward cushion element may be inserted laterally, as a unit, in the forward opening in the yoke, and a draw-bar slidably engaging said yoke, substantially as described. 100
3. In a draft rigging, the combination of 105 a yoke having an integral barrel in the rear end thereof, a pair of full size cushion elements, one of which is accommodated in said barrel, a plate extending across the open end of the barrel and serving as a bearing for the rear end of the forward cushion element, a front follower, a plunger extending from 110 the follower through said plate and having a head adapted to bear on the forward end of the rear cushion element, said head being countersunk in the plate in order that the inner face of the head may lie substantially in the plane of the forward edge of the barrel, and a drawbar slidably engaging said 115 yoke, substantially as described.
4. In a draft rigging, the combination of 120 a yoke having a barrel of a length equal to substantially one-half the spring space in the yoke, a pair of cushion elements, one of which is accommodated within said barrel, a plate overlying the open end of the barrel, said plate having a flared axial opening therein, the large diameter of the opening being substantially equal to the external diameter of the cushion elements employed, the small diameter of the opening being substantially equal to the diameter of the internal opening in said cushion elements, a front follower, a plunger, abutting said follower 125 130

and having its rear end shaped to fit the flared opening in the plate and terminating in substantially the plane of the rear surface of the plate, and a draw-bar slidably 5 engaging the yoke, substantially as described.

5. In a draft rigging, the combination of a yoke having a barrel of a length equal to substantially one-half the spring space in 10 the yoke, a pair of cushion elements, one of which is accommodated within said barrel, a plate overlying the open end of the barrel, said plate having a flared axial opening therein, a plunger having an end fitting said 15 flared opening, a front follower, means for interlocking the follower and plunger against lateral displacement, the arrangement being such that said plate, plunger, front cushion element and follower may be inserted laterally as a unit in the forward end of the yoke, substantially as described.

6. In a draft rigging, the combination of a yoke, the rear portion of which is in the form of a barrel, a pair of tandem cushion 25 elements, one of which is entirely inclosed within said barrel, a plate bearing on the forward edge of the barrel and serving as a bearing for the forward cushion element, a 20 bearing for the forward cushion element, a

plunger extending through said plate and having a head which is countersunk in the plate whereby the plunger terminates at the forward edge of the barrel, a front follower to which said plunger is connected, and a draw-bar slidably engaging said yoke, substantially as described. 30

7. In a draft rigging, the combination of a yoke, the rear portion of which is in the form of a barrel, a pair of tandem cushion elements, one of which is entirely inclosed within said barrel, a plate bearing on the 40 forward edge of the barrel and serving as a bearing for the forward cushion element, said plate having a non-circular opening therethrough, a front follower, a plunger having a horizontally curved forward end 45 engaging said follower and shaped to fit the non-circular opening in said plate whereby the plunger is prevented from rotating and changing the relation of the curved end to the follower, substantially as described. 50

Signed at Chicago, Ill., this 10th day of April, 1918.

GEORGE L. HARVEY.
